Primary Examiner — Nathaniel D. Buckner(74) *Attorney, Agent, or Firm* — Wagenknecht IP Law Group, PC(57) **CLAIM**

The ornamental design for a charging adapter, as shown and described.

DESCRIPTION

FIG. 1 is a top, front and left perspective view of a charging adapter showing our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof;

FIG. 7 is a rear elevational view thereof;

FIG. 8 is a top front left perspective view thereof, shown in an environment of use; and,

FIG. 9 is a top front left perspective view thereof, shown in a second environment of use.

The broken lines in the figures depict portions of the charging adapter and environmental subject matter which form no part of the claimed design.
